No. 660,310.

Patented Oct. 23, 1900.

J. RANZ.

SAW SETTING DEVICE.

(Application filed Nov. 11, 1899.)

(No Model.)

UNITED STATES PATENT OFFICE.

JACOB RANZ, OF ST. LOUIS, MISSOURI.

SAW-SETTING DEVICE.

SPECIFICATION forming part of Letters Patent No. 660,310, dated October 23, 1900.

Application filed November 11, 1899. Serial No. 736,583. (No model.)

To all whom it may concern:

Be it known that I, JACOB RANZ, a citizen of the United States, residing at the city of St. Louis, State of Missouri, have invented a certain new and useful Improvement in Saw-Setting Devices, of which the following is a full, clear, and exact description, such as will enable others skilled in the art to which it appertains to make and use the same, reference being had to the accompanying drawings, forming part of this specification, in which—

Figure 1 is a top plan view of my improved saw-setting device. Fig. 2 is a vertical longitudinal sectional view through the same on line 2 2, Fig. 1, the device being shown in position on the saw. Fig. 3 is a horizontal sectional view on line 3 3, Fig. 2. Fig. 4 is a horizontal sectional view on line 4 4, Fig. 6. Fig. 5 is a horizontal sectional view on line 5 5, Fig. 2. Fig. 6 is a rear end elevational view of the device. Fig. 7 is a vertical cross-sectional view through the device on line 7 7, Fig. 2; and Fig. 8 is a vertical sectional view on line 8 8, Fig. 2.

This invention relates to a new and useful improvement in a machine for setting the teeth of saws, the object being to provide a device of the character described which can be easily applied in position and readily adjusted to accommodate itself to the different-sized teeth and one which is compact, simple, cheap, and can be manually operated with the exertion of comparatively little power.

With these objects in view the invention consists in the construction, arrangement, and combination of the several parts, all as will hereinafter be described, and afterward pointed out in the claims.

In the drawings, X indicates a portion of a saw-blade upon which my improved machine is mounted for the purpose of setting the teeth thereof, said blade in practice being preferably supported in a vertical position, as by the employment of a vise.

The body portion of the machine consists of a casting A, preferably made of steel and shaped to accommodate the several moving parts. Two jaws depend from this body portion and are adapted to receive the saw-blade therebetween, said jaws being provided on their inner faces with face-plates B and B',

the former of which is preferably fixed in position by suitable screws, while the latter is capable of moving laterally, being guided in such movement by guide-pins b, secured thereto, but moving freely in openings in one jaw of the main frame.

When the device is set in position on the saw, a handle C, extending from the side thereof, preferably the left, so that the operator may support the machine in its movement, is turned so that a threaded extension on its inner end will engage with the face-plate B' to force the same laterally against the saw-blade, clamping the blade in position, but leaving sufficient clearance to permit the face-plates to move along the surface of the blade without undue friction. A jam-nut C' locks the handle C in position after the face-plate B' has been adjusted. From the above it will be seen that saw-blades of different thicknesses are accommodated between the face-plates, one of which is adjustable, so as to hold the frame firmly on the blade, sufficient clearance being left to enable the frame to move along the blade, and that means are also provided for locking this adjustable face-plate in its position against the blade.

As shown in Figs. 6 and 7, the face-plates above described do not extend to the top of the groove in the lower portion of the frame, but terminate a sufficient distance underneath to permit the free movement of the laterally displaced or "set" teeth without binding, the machine riding on said teeth.

Mounted in what I will term the "forward end" of the frame is a vertically-disposed shaft or stud D, preferably formed with a circumferentially-disposed groove, in which fits a cross-pin d, permitting rotation thereof, but preventing vertical displacement. The upper end of shaft D has a hub E secured thereon by means of a suitable set-screw or other fastening device, from which hub extends an operating-handle E'. Hub E is provided with a base-flange e and laterally-projecting stops e', which coöperate with adjusting-screws F, threaded in lugs extending from the upper portion of the main frame. These adjusting-screws are provided with suitable knurled heads at their rear ends by which they may be readily rotated, while jam-nuts

f, threaded thereon, are adapted to impinge against the rear face of the lug and lock said screws in their adjusted positions. By means of a handle *E'* a rocking motion is imparted 5 to the shaft *D*, the limits of which motion are diminished or increased by adjusting the nuts *f*, which coöperate with the stops *e'*, as will be obvious. The lower end of shaft *D* terminates slightly above the groove in the bottom 10 of the frame and is provided with projections *d'*, whose cross-sectional shape is best illustrated in Fig. 3. These projections extend from opposite sides of the shaft, a sufficient space being left therebetween for the 15 passage of the saw-teeth, and when the shaft carrying the projections is rocked said projections alternately come in contact with alternate saw-teeth and bend or set such teeth in opposite directions, as shown in Fig. 3, the 20 face-plates *B* and *B'* acting in this operation to firmly support the blade proper of the saw at the point where this lateral strain or twisting action is applied.

In order to feed the machine along the saw 25 so that the projections *d'* will properly operate upon the teeth, I provide a double-faced cam *G* on the spindle or shaft *D*, (see Fig. 5,) which coöperates with and imparts a reciprocating motion to a feeding device, which consists of a slidable bar *H*, provided with a lug or projection *h* in the path of the cam, said lug or projection being forced inwardly toward the shaft *D* by means of a compression-spring *I*. The body portion of the bar *H* is 30 provided with a threaded socket which receives the inner end of an adjusting-screw *J*, whose outer end passes freely through a box *K*, beyond which said screw is provided with a knurled thumb-nut whereby the projection *h* may be adjusted toward or from the box *K* 35 or toward or from the cam *G*. Box *K* is held from rotation on screw *J* by means of lugs projecting rearwardly from the main frame. (See Figs. 5 and 6.)

45 *L* indicates a ratchet-like tooth provided with a slot at its upper end for embracing bolt *J*, (see Figs. 2 and 8,) which tooth is held normally in its lower position by a spring *l*, bearing against the upper face thereof. The 50 tooth and spring are introduced from above and a hollow cap *k* secured in place to hold said parts in position. The downward movement of tooth *l* is limited by the upper end of the slot engaging the rod *J*, as seen in Fig. 8.

55 In order to adjust the box *K* backwardly and forwardly so that the projection *d'* will strike the saw-tooth at the proper point, I arrange a screw-bolt *M* in a projection extending laterally from box *K*, which inner end is 60 designed to impinge against the rear face of the frame and adjust the box *K* relative thereto. The object in adjusting the box *K* relative to the frame can be readily appreciated from the following statement: In Fig. 2 the 65 feeding-tooth is in engagement with a saw-tooth and the projection *d'* (on the far side of shaft *D*) is operating upon a saw-tooth.

There are ten saw-teeth between the feeding-tooth of the machine and the saw-tooth being operated upon. If the machine were used 70 on a different saw the base-line of whose teeth were greater or less than the base-line of the teeth shown in the drawings, the feeding-tooth *L* in feeding against the shoulder of the tooth would perhaps so position the machine 75 on the saw that the projection *d'* instead of coöperating with the apex of a tooth would engage two teeth, and therefore it is necessary to adjust box *K* so that the projections *d'* will occupy proper positions with respect to 80 the saw-teeth to be operated upon. After this adjustment has been secured the screw *J* is operated to adjust the projection *h* toward and from the cam *G*, so that the throw of said cam in operating the box *K* will so 85 move said box that the machine will be advanced just exactly the distance of one tooth at each operation of the handle *E'*. The handle *C* is designed to be grasped in the left hand of the operator, as before stated, and 90 turned up, so that the adjustable face-plate offers a firm support for the blade while its teeth are being operated upon by the projection on the vertical spindle. The handle *E'* is now operated, it being oscillated to the 95 full limit of its movement, as regulated by the stops *F*. At each oscillation of the handle *E'* the spindle *D* is rocked, so that the projections *d'* contact with alternate teeth, respectively, of the saw. Coincident with the 100 rocking of the spindle *D* the cam *G* moves past the projection *h*, forcing the box *K* to the rear, and tooth *L* being in engagement with the saw-tooth will force the machine forwardly the distance of one saw-tooth, proper 105 adjustment for such advance having been previously made. Before the cam *G* moves the box rearwardly to advance the machine the projection *d'* will have performed its work in setting its tooth and will be moved out of 110 the way of the teeth, the opposite projection coming in position to operate on the next tooth in advance at about the time that the projection *h* is riding down the face of cam *G* at or near the completion of its final or inward movement. This inward or forward movement of box *K* results from the action 115 of spring *I*, and tooth *L* in such forward movement rides over a saw-tooth, compressing spring *l* in such action, as is well understood. 120 From the above it will be noted that the machine is automatically advanced along the saw, the feeding-tooth making a complete vibration of each stroke of the handle *E'*, whether forward or backward, and that each 125 stroke of said operating-handle causes one of the setting projections to engage with a saw-tooth and set said tooth laterally at a greater or less angle, depending upon the point of arrest of the handle, determined by the adjustment of the bolts *F*. In this manner, the parts being properly adjusted beforehand, all 130 that is necessary to set the teeth of a saw, the machine being placed in position, is to oscillate

late the handle E', the machine automatically feeding itself forward and leaving practically nothing for the operator to do but work the handle E'.

5 The frame A is preferably cut away, as at a, in order that the operator can see how and where the projections d operate upon the saw-teeth in order that the bolts F, J, and M may be properly adjusted.

10 With respect to the axis of rotation of the rocking or oscillating shaft D the projections d' move in an arc of a circle; but by reason of the forward travel of the device this arc is extended, so that the projections travel in a 15 path described by a cycloidal groove. This is of great advantage in that when the projections engage with the teeth to bend them laterally the bend imparted to said teeth is not a straight angle starting from the base-line, but is in the form of a groove both laterally, as shown in Fig. 6, and rearwardly, as shown in Fig. 3, giving to the teeth a twisted appearance. By this formation should the apices of the teeth become worn a cutting 25 edge would still remain, while in the straight angular formation, the angle starting from the base-line, the wearing of the apices of the teeth detracts from the cutting qualities of the saw in proportion to the cutting edge 30 worn off. This is quite serious at times, especially when a wood-saw strikes metal, as a nail, said metal tending to strip the saw-teeth of their effective cutting edges.

I am aware that minor changes in the arrangement, construction, and combination of the several parts of my device may be made and substituted for those herein shown and described without in the least departing from the nature and principle of my invention.

40 Having thus described my invention, what I claim, and desire to secure by Letters Patent, is—

1. In a saw-setting machine, the combination with a frame, of the setting mechanism 45 mounted in said frame, said frame being provided with a groove in its lower face, across which the setting mechanism operates, face-plates arranged in said groove and extending on each side of the setting mechanism, said 50 face-plates forming substantially a T-shaped groove, in the vertical member of which the body of the saw-blade is located, while the set teeth traverse the enlarged space, and means for adjusting one of said face-plates 55 to accommodate different thicknesses of saw-blades; substantially as described.

2. In a saw-setting machine, the combination with a frame, of a rocking shaft mounted therein and provided with projections extending from opposite sides of the end of said shaft, the working faces of said projections being substantially parallel to the axis of rotation of said shaft, and a handle for rocking said shaft; substantially as described.

65 3. In a saw-setting machine, the combination with a grooved frame, of a rocking shaft mounted in said frame, projections d' extend-

ing from the end of said shaft and adapted to traverse the grooves to set the saw-teeth, means for adjustably limiting the travel of 70 said setting device across such groove, and a handle for operating said shaft; substantially as described.

4. In a saw-setting machine, the combination with a grooved frame, of a rocking shaft 75 mounted therein and carrying setting projections d' on its end, which projections are arranged diametrically opposite each other, and partially traverse the groove in operation, means for arresting and adjustably limiting 80 the motion of said shaft to control the throw of said projections, and a feeding mechanism operated by said shaft; substantially as described.

5. In a saw-setting machine, the combination with a grooved frame, of a shaft mounted in said frame in axial alinement with the groove in said frame, setting devices arranged at one end of said shaft, a cam on the other end of said shaft, and a feeding mechanism 90 operated by said cam; substantially as described.

6. In a saw-setting machine, the combination with a frame provided with a groove in its under side, of a rocking shaft mounted in 95 the front end of said frame and in axial alinement with said groove, setting devices on the inner end of said shaft which partially traverse the groove in the frame, a cam arranged on said rocking shaft, a sliding bar mounted 100 in the frame and coöperating with said cam, a spring for holding said bar forwardly against the cam, and a yielding tooth arranged on the rear end of the bar and projecting into the path of the teeth of the saw received by the groove 105 in the frame, substantially as described.

7. In a saw-setting machine, the combination with a frame, of a shaft or spindle carrying setting devices, a cam arranged on said shaft, a sliding bar provided with a projection in the path of said cam, a yielding tooth carried by said bar, and means for adjusting the distance between said tooth and the projection in the path of said cam; substantially 110 as described.

8. In a saw-setting machine, the combination with a shaft carrying saw-setting devices, a cam on said shaft, a sliding bar provided with a projection in the path of said cam, a spring for forcing said bar inwardly toward 120 the shaft, a bolt having a threaded connection with said bar, and a spring-pressed tooth carried by said bolt; substantially as described.

9. In a saw-setting machine, the combination with a setting device, of a cam which is 125 operated in connection therewith, a feeding mechanism actuated by said cam, said feeding mechanism including the projection in the path of the cam, a spring-pressed tooth, means for adjusting the distance between said 130 tooth and the projection in the path of the cam, and means for bodily adjusting the tooth and said projection; substantially as described.

10. In a saw-setting machine, the combina-

- tion with setting devices, of a cam operated in connection therewith, a feeding mechanism coöperating with said cam, said mechanism comprising a projection in the path of movement of the cam, a tooth, means for adjusting said tooth toward or from the saw-setting device, and means for adjusting the projection toward or from its operating-cam; substantially as described.
- 10 11. In a saw-setting machine, the combination with a grooved frame for receiving the saw to be set, of a shaft mounted in said frame and carrying projections for alternately engaging the different teeth of the saw to be set,
- 15 an operating-handle attached to said shaft, means for adjustably limiting the rotary

movement of said shaft, a cam carried by said shaft, a spring-pressed rod having a projection in the path of movement of said cam, a box adjustably carried on the outer end of said rod, means for adjusting said box relative to the frame, and a spring-pressed feeding-tooth mounted in said box; substantially as described.

In testimony whereof I hereunto affix my signature, in the presence of two witnesses, this 7th day of November, 1899.

JACOB RANZ.
